UNITED STATES PATENT OFFICE.

PHILLIP H. HOHMAN AND EZRA E. INNIS, OF LAUREL, MONTANA.

STOVE.

1,421,233.

Specification of Letters Patent. Patented June 27, 1922.

Application filed February 9, 1920. Serial No. 357,335.

To all whom it may concern:

Be it known that we, PHILLIP H. HOHMAN and EZRA E. INNIS, citizens of the United States, residing at Laurel, in the county of 5 Yellowstone and State of Montana, respectively, have invented new and useful Improvements in Stoves, of which the following is a specification.

This invention comprehends the provision 10 of a stove designed to be carried by an automobile or the like, wherein the exhaust gases are utilized as the heating agent.

In carrying out the invention, use is made 15 of a receptacle wherein the sides and back include spaced walls defining chambers through which the exhaust passes, the chambers having positioned therein baffles of different construction that cause the exhaust gases to pursue a zig-zag course in passing 20 from one chamber to the other, so as to effectively heat the interior of the stove, before the gases are exhausted to the atmosphere.

Another important object of the invention, resides in the novel manner of closing 25 the containers removably positioned within the stove and providing a valve controlled vent for the containers.

The nature and advantages of the invention will be better understood when the following detail description is read in connection 30 with the accompanying drawings, the invention residing in the construction, combination and arrangement of parts as claimed.

35 In the drawings forming part of this specification, like numerals of reference indicate similar parts in the several views and wherein:

Figure 1 is a view in elevation of the stove 40 forming the subject matter of the invention.

Figure 2 is a front view showing the door opened.

Figure 3 is a vertical sectional view taken on the line 3—3 of Figure 1.

45 Figure 4 is a horizontal sectional view taken through the stove.

Figure 5 is a sectional view taken through one end of the stove.

Figure 6 is a sectional view taken through 50 the back of the stove.

Figure 7 is a perspective view with the top removed.

The stove forming the subject matter of 55 this invention, is preferably in the nature of a receptacle indicated generally at 10, and

which may be of any suitable size, and cross sectional configuration. The receptacle herein shown consists of a back wall 11 a bottom 12, end walls 13, a door 14, the latter constituting the front wall of the receptacle, 60 and a top 15 which is hingedly mounted as at 16. The back and two ends are made up of spaced walls to define chambers 17 through which the exhaust from the motor passes in its course through the atmosphere. As hereinabove stated, the stove is primarily intended for use in connection with automobiles or the like, and may be positioned at any convenient or desirable location on the car and connected with the exhaust by means of the 65 pipe 18, the latter leading from the exhaust pipe into one of the chambers 17. The bottom 12 is formed with depressions 20 for the reception of the cooking vessels or the like indicated at 21. Arranged within the stove, 70 is a top or cover 23 for each of the cooking vessels, the tops being associated with coiled springs 24, which function to effectively maintain the closure of the tops in position upon the vessels as shown. Each closure or 75 top 23 is associated with the pipe 25 which communicates with the vent pipe 27 to allow for the escape of steam from the vessels as will be readily understood. The chambers 80 17 are separated by the partition 28 which 85 extends across the receptacle in the space between the bottoms thereof as illustrated, this partition forming part of a curved baffle plate 29 which is arranged in the space between the rear walls and curved upwardly 90 and in the direction of one end of the receptacle. This baffle is continued as at 30 and extended across one end of the receptacle terminating short of or in spaced relation to the front wall of the receptacle. An additional baffle plate 31 is arranged in the space 95 between the rear walls of the receptacle and extended longitudinally thereof from the baffle plate 29 to the opposite end of the receptacle, this baffle being continued as at 32, 100 the portion 32 being curved upwardly and forwardly in the space between the said end of the receptacle terminating in spaced relation to the front wall of the receptacle as shown. It will be noted that the exhaust is 105 conveyed into one of the chambers 17 through the pipe 18, the exhaust filling the space between the bottoms of the receptacle in this particular chamber and also the space between the ends and rear walls of the recep- 110

tacle. The exhaust circulates about this chamber 17 as indicated by the arrows in Figure 7, striking the baffle plates 29 and 30 which directs the exhaust to pursue the course indicated by the arrows over the baffle plate 30 and thence rearwardly to fill the space between the rear walls of the receptacle about the baffle plate 31. The baffle plate 31 directs the exhaust toward one end of the receptacle as indicated by the arrows, filling the space at this end of the receptacle, wherein the exhaust is directed by the baffle plate 32 to pass between the forward end of this baffle plate and the adjacent wall of the receptacle, under the baffle plate 32 and thence into the chamber 17 at the right side of the partition 28 as illustrated in Figure 7, filling the space between the bottoms of the receptacle in this particular compartment, and finally escaping to the atmosphere through the pipe 33. While in use, the top 15 and the door 14 are effectively closed and maintained in closed position in any suitable manner. When it is desired to remove the vessels 21, the latter are slightly elevated against the tension of the springs 24 and removed through the open front of the stove.

While it is believed that from the foregoing description, the nature and advantages of the invention will be readily understood,

we desire to have it understood that we do not limit ourselves in the construction herein shown and described, and that such changes may be resorted to when desired as fall within the scope of what is claimed.

35

Having thus described our invention what we claim as new is:

A stove for automobiles, comprising a receptacle provided with spaced walls, a door controlling access to the receptacle, a pipe connected to the exhaust pipe of the automobile and extending into said receptacle between said spaced walls, baffle plates disposed between the spaced walls of said receptacle, vessels removably positioned in the receptacle, a cover for each of said vessels, a horizontal vent pipe extending into said receptacle above said covers, vertical pipes extending from said covers and communicating with said vent pipe, a cover hingedly secured to said receptacle, coil springs secured to the bottom of said cover and adapted to engage said vent pipe, and a pipe extending into said receptacle between said spaced walls and communicating with the atmosphere.

In testimony whereof we affix our signatures.

PHILLIP H. HOHMANN.
EZRA E. INNIS.
